UNITED STATES PATENT OFFICE.

JOHN E. DREW, OF JERSEY CITY, NEW JERSEY, ASSIGNOR TO WADE AND BUTCHER CORPORATION, A CORPORATION OF NEW JERSEY.

METHOD OF MAKING CURVED RAZOR BLADES.

Application filed August 21, 1926. Serial No. 130,680.

This invention relates to an improved method of making a curved blade for safety razors.

Many attempts to produce a perfect safety razor have been made and many millions have been sold and passed into the possession of the public. One of the most popular type employed a thin flexible blade which was flat as made, but was bent and clamped between a curved support and a curved safety guard, when in use, in order to give the necessary rigidity to the cutting edge of the blade. These blades were approximately .006" thick and their cutting edges were formed midway between their broad surfaces, so that the cutting edge was approximately .003" from the safety guard against which the blade was clamped. This distance between cutting edge of blade and guard was sufficient for shaving purposes when the beard of the user was not too stiff; but in many cases of stiff beards, this distance was insufficient to cause the cutting edge of the blade to bite the hair and shave it off cleanly. Apparently, no attempt has been made through the years to ascertain the best or most efficient distance between the edge of such a razor blade and the guard, for it has been found that different safety razors vary very much in this respect.

By experimentation and careful tests, it has now been discovered what the efficiency curve of safety razors is, and what change in new and existing razors or blades will increase the efficiency of such razors as shaving instruments. While the guard of new safety razors may be so constructed as to provide this increased efficiency, it is entirely impracticable to recall and change the guards on the millions of razors already in possession of the public. The main object of the present invention is the production of a very simple and efficient method of making a curved replacement blade which, when used either in a new razor or in any of the millions already in possession of the public, will automatically so position the cutting edge of the blade with respect to the safety guard that the distance between said cutting edge and said guard will represent the peak, or approximately the peak, of the efficiency curve of the razor. Another object is the production of a method of making a permanently curved replacement blade for safety razors, the cutting edge of the blade being

approximately .010" from an arcuate projection of its concave surface, so that when used in a new or old safety razor, the distance between its cutting edge and said guard will be automatically determined and will represent the peak, or substantially the peak, of the efficiency curve of the razor. With these and other objects not specifically mentioned in view, the invention consists in certain acts or steps, and series of acts or steps, which will be hereinafter fully described and then specifically set forth in the claims hereunto appended.

In the accompanying drawings, Fig. 1 is a perspective view of a blank which is the result of the first act or step of the new method; Fig. 2 is a sectional view of two bending and cooling dies between which the blank of Fig. 1, after heating to a tempering heat, is placed and simultaneously bent and cooled to permanently curve it without setting up internal strains, and to harden it; and Fig. 3 is illustrative of the step of the method in which cutting edges are formed on the hard curved blade and located a predetermined distance from an arcuate projection of the concave surface of the blade in order to bring the cutting edges into such relationship with said surface that when the blade is assembled with its holder, said edges will be at the peak, or substantially at the peak, of the efficiency curve of the razor.

In carrying the invention into effect, a flat blank is first stamped from sheet steel. Such a blank is shown in Fig. 1 and marked 4. It is produced on an ordinary punch press.

The blank is then heated to the usual tempering heat in an ordinary heating furnace.

In order to produce from the heated blank a permanently curved and hard and unstrained blade, the heated blank is then simultaneously bent and cooled between dies 5 and 6 each of which is water cooled by means of pipes 7 through which water is caused to circulate by means not shown but of well known construction and operation. At the completion of this step of the method, the blank 4 will have become a blade having a curved mid-section 8 and reversely curved edge-sections 9, 9, the curvature being greatly exaggerated in the drawings in the interest of clearness. Actually, the edge-sections are reversely curved only sufficiently to cause their extreme edges that were bent from an arcuate projection of the concave surface

of the blade to lie approximately .010" from said projection as indicated in Fig. 3.

By thus bending the blank while it is cooling, all internal stresses are absorbed, and the resultant blade is unstrained as well as hard.

By bending the edge-sections away from the arcuate projection of the concave surface of the blade, a grinding operation is eliminated and only one is necessary, that one being on the convex side of the blade as indicated in Fig. 3 where two grinding wheels 10 are shown as in engagement with the edge-sections of the blade, to simultaneously 15 grind the opposite cutting edges.

The next step is the honing of the ground edges, and this is preferably done on both sides of the cutting edges. And the final step is the stropping of the honed edges, and 20 this is preferably done on both sides of the cutting edges. The honing and stropping may be done by hand or by any suitable means or mechanism.

What is claimed is:

- 25 1. The method of making a curved razor blade, which consists in stamping a flat blank from sheet steel, then heating said blank to a tempering heat, then simultaneously bending and cooling the heated blank to produce a permanently curved and hard and unstrained blade, then grinding said blade to form cutting edges thereon, then honing the ground edges, and then stropping the honed edges.
- 30 2. The method of making a curved razor blade, which consists in stamping a flat blank from sheet steel, then heating said blank to a tempering heat; then simultaneously bending and cooling the heated blank to harden and permanently curve its mid-section and reversely curve its edge-sections and thus produce a hard and unstrained reversely curved blade, then grinding the convex side only of said blade to form cutting edges thereon.
- 35 3. The series of steps in a method of making a curved razor blade, which consists in heating a flat blank to a tempering heat, then simultaneously bending and cooling the heated blank to harden and permanently curve its mid-section and reversely curve its edge-sections and thus form a hard and unstrained reversely curved blade, then grinding the convex side only of said blade to form cutting edges thereon, then honing both sides of the ground edges, and then stropping both sides of the honed edges.
- 40 4. The series of steps in a method of making a curved razor blade, which consists in heating a flat blank to a tempering heat, then simultaneously bending and cooling the heated blank to harden and permanently curve its mid-section and reversely curve its edge-sections and thus produce a hard and unstrained reversely curved blade.
- 45 5. The series of steps in a method of making a curved razor blade, which consists in heating a flat blank to a tempering heat, then simultaneously bending and cooling the heated blank to harden and permanently curve its mid-section and reversely curve its edge-sections and thus produce a hard and unstrained reversely curved blade, the curvature of said blade being such that opposite edges of the blade lie approximately .010" from an arcuate projection of the concave surface of the blade's mid-section.
- 50 6. The series of steps in a method of making a curved razor blade, which consists in heating a flat blank to a tempering heat, then simultaneously bending and cooling the heated blank to produce a permanently curved and hard and unstrained blade, then grinding said blade to form cutting edges thereon.
- 55 7. The series of steps in a method of making a curved razor blade, which consists in heating a flat blank to a tempering heat, then simultaneously bending and cooling the heated blank to harden and permanently curve its mid-section and reversely curve its edge-sections and thus form a hard and unstrained reversely curved blade, then grinding the convex side only of said blade to form cutting edges thereon.
- 60 8. The series of steps in a method of making a curved razor blade, which consists in heating a flat blank to a tempering heat, then simultaneously bending and cooling the heated blank to harden and permanently curve its mid-section and reversely curve its edge-sections and thus form a hard and unstrained reversely curved blade, then grinding the convex side only of said blade to form cutting edges thereon, then honing both sides of the ground edges, and then stropping both sides of the honed edges.

In testimony whereof, I have signed my name to this specification.

JOHN E. DREW.
